UNITED STATES PATENT OFFICE.

ALEXIS R. PRIBIL, OF CLEVELAND, OHIO.

PROCESS OF MAKING PISTONS.

1,293,916.

Specification of Letters Patent. Patented Feb. 11, 1919.

Original application filed December 26, 1916, Serial No. 138,956. Divided and this application filed October 31, 1917. Serial No. 189,423.

To all whom it may concern:

Be it known that I, ALEXIS R. PRIBIL, a citizen of the United States of America, residing at Cleveland, in the county of Cuyahoga and State of Ohio, have invented certain new and useful Improvements in Processes of Making Pistons, of which the following is a specification, reference being had therein to the accompanying drawings.

10 This invention relates to pistons and relates more particularly to divisional matter not claimed, but disclosed in my pending application filed Dec. 26, 1916, Serial No. 138,956.

15 The object of the present invention is to provide a piston body or shell that may be made from flat hot rolled blue annealed open hearth steel or any suitable material that will provide a rigid and durable piston shell or skirt, the flat stock being given a cylindrical form with the longitudinal edges butt welded or otherwise joined, and with a head locked in the body or shell by bringing the flat stock to cylindrical form.

20 A further object of my invention is to provide a piston formed in the above manner which may have interior reinforcements, and more particularly a novel pin support which will brace the head of the piston and relieve the shell or side wall thereof of any stresses or strains relative to a connecting rod.

25 The invention possesses other advantages than those above enumerated, and reference will now be had to the drawing, wherein—

Figure 1 is a longitudinal sectional view of the piston in accordance with my invention;

30 Fig. 2 is a view of the inner end of the piston, and

Fig. 3 is a plan of a piece of stock from which the piston body or shell may be formed.

35 To put my invention into practice, I take a piece of flat hot rolled blue annealed open hearth steel or a piece of light and durable metal that may be rolled and shaped to cylindrical form. The piece of flat metal is designated 1, and I next subject this piece 40 of metal to the action of the rolls, so as to provide the piece of metal with longitudinal raised portions 2, 3, and 4, also upstanding flanges 5 and 6. The raised portions 3 provide parallel grooves in the outer face of the

piece of metal contiguous to the flange 6 and the raised portion 2 provides a groove adjacent the flange 5. The raised portion 4 is punched or stamped to provide outstanding tubular holders 7 and these holders are spaced equi-distant from the ends of the piece of stock and located relative to each other so that said holders will be in opposed relation when the piece of stock is brought to cylindrical form.

45 The next step in the process of producing a piston is that of providing a head 8, which may be made of a metal of greater thickness than the piece of stock 1. The head 8 is cut and stamped in circular form with an annular depressed and outwardly extending edge 9, and this annular edge of the head is adapted to be received between the flange 6 and the outermost raised portion 3 of the piece of stock 1, when brought to cylindrical form. By placing the edge 9 of the head 8 in the groove 10 formed by the flange 6 and the outermost raised portion 3, the rolled and grooved piece of stock may now be bent about the edge of the head and to cylindrical form, so that the ends of the piece of stock will abut and may be butt welded or otherwise connected together, thus locking the head 8 in the outer end of the piston body or shell. The tubular holders 7 will then be in diametrically opposed relation 50 and may receive bushings 11 for a pin 12 by which a connecting rod 13 may be articulated with the piston.

55 The raised portion 4 affords a wide annular groove in the outer wall of the cylindrical piston body or shell, thus providing an annular lubricant pocket for holding a lubricant during the reciprocation of the piston in a cylinder.

60 The grooves formed by the raised portions 2 and 3 may accommodate suitable packing rings, and the head 8 may be reinforced by a yoke or pin support 14. This yoke or pin support may be made of metal of the same gage as the head 8 or much heavier than said head or the stock from which the piston body or shell is formed. It is preferable to use channel material and provide the ends of the yoke or support with bearings 15 alining with the tubular holders 7, so as to receive the bushings 11 and thus transfer any stresses or strains of the connecting rod 13 through the pin 12 to the

yoke or support 14 instead of to the walls of the body or shell. Besides distributing the compression strain, the yoke or pin support provides radiating means for heat, and 5 allows light metal to be used for the body or skirt of the piston.

It is thought that the manner of forming the piston and its utility will be apparent without further description, and while in 10 the drawing there is illustrated a preferred embodiment of my invention, it is to be understood that the structural elements are susceptible to such variations and modifications as fall within the scope of the appended claims.

What I claim is:

1. A process of making pistons, consisting of providing a flat piece of metal with raised portions to form a flange on one side 20 of the piece of metal and at one end thereof, and grooves in the other side of the piece of metal, bending the piece of metal to cylindrical form and connecting the confronting edges thereof, and locking a piston head 25 between said flange and one of the raised portions when the piece of metal is brought to cylindrical form.

2. A process of making a piston, consisting in providing a piece of flat metal with grooves and tubular holders, bending the 20 piece of metal to cylindrical form to bring the edges thereof together and said tubular holders in opposed relation, and securing a piston head in position by having the piece of metal bent about and on to the edges of 35 said head.

3. A process of making a piston consisting of rolling and punching a piece of flat stock to provide grooves and tubular holders, bending the piece of stock to cylindrical 40 form so as to bring the edges thereof into abutting relation and said tubular holders in opposed relation, locking a piston head in position when bending the piece of stock to cylindrical form, and then securing a pin 45 support to said head with portions thereof alining with said tubular holders.

In testimony whereof I affix my signature in the presence of two witnesses.

ALEXIS R. PRIBIL.
